UNITED STATES PATENT OFFICE.

WILLIAM H. INSLEY, OF INDIANAPOLIS, INDIANA, ASSIGNOR TO INSLEY MANUFACTURING COMPANY, OF INDIANAPOLIS, INDIANA, A CORPORATION OF INDIANA.

LINE-GATE FOR CONCRETE-CHUTES.

1,125,105.

Specification of Letters Patent.

Patented Jan. 19, 1915.

Application filed December 12, 1913. Serial No. 806,200.

To all whom it may concern:

Be it known that I, WILLIAM H. INSLEY, a citizen of the United States, residing at Indianapolis, in the county of Marion and 5 State of Indiana, have invented a new and useful Line-Gate for Concrete-Chutes, of which the following is a specification.

The object of my invention is to produce an improvement in pouring chutes commonly used in the erection of reinforced concrete buildings for delivering the fresh concrete mixture to desired points, the invention being particularly directed to that portion of the apparatus by which the stream 10 may be deflected from a main trunk line into short laterals.

The accompanying drawings illustrate my invention.

Figure 1 is a side elevation of a fragment 20 of a trunk line chute equipped with my improvement; Fig. 2 a plan; Fig. 3 a section on line 3—3 of Fig. 1; and Fig. 4 an elevation of a fragment of the trunk line chute with the valve omitted.

In the drawings, 10 indicates the main 25 trunk line chute of ordinary type braced at sufficiently separated points by the binding straps 11, 11. Between the binders 11 the under side of the chute 10 is cut away in 30 the manner illustrated in Fig. 4, the upper or initial end being first cut inwardly substantially square, as indicated at 12, then longitudinally, as indicated at 13, then upwardly and forwardly, as indicated at 14, 35 and then forwardly and downwardly as indicated at 15. Adjacent the part 15, at each side, the chute 10 is provided with a downwardly extending ear 16 which extends over the cut away portion and is provided with 40 an opening for the reception of a pivot bolt 17. The two pivot bolts carry the opposite sides of a trough-shaped valve 18 adapted to fit in the opening 12—13—14—15, in the manner clearly illustrated in Fig. 1, the 45 lower forward end of the trough lying inside of the trunk line chute while the upper rear end of the valve lies outside of the trunk line chute, this arrangement being permitted by the formation of a notch 19 in 50 the upper edge of each side of the trough and the slight outward displacement of the edge of the valve to the rear of the notch and a slight inward displacement of each edge of the trough forward of the notch so

that that portion of the wall of the trunk 55 line chute at the corner between the parts 14 and 15, will lie in the notch 19.

Secured rigidly to one side of the valve 18 is an operating arm 20 which is also conveniently pivoted upon one of the pivot 60 bolts 17 and extended from thence forwardly and downwardly for the reception of a pull rope 21. The upper rearward end of the valve 18 is provided with a strengthening binding strip 22 which at its ends is turned 65 outwardly to form fingers 23 beneath which the hooked ends of catches 24 may pass. The catches 24 are conveniently formed at the ends of a yoke or U-shaped bar 25, the central portion of which bridges the main 70 chute 10 and is pivotally supported in inverted U-shaped brackets 26 pivoted or otherwise suitably secured to the upper edges of the chute 10.

The hooks 24 are normally urged to valve 75 retaining position by a suitable spring 27.

Suspended from the chute 10 by suspender straps or yokes 28, 28 is a hopper 29 suitably notched at its front and rear edges, as indicated at 30, to straddle the under side of the 80 chute 10 above and below the valve 18. Mounted upon the hopper 29 is a sheave 31 which serves as a guide for a pull rope 32 attached to the yoke 25.

Under normal conditions the position of 85 the parts is that shown in Fig. 2, so that material, flowing through chute 10, will flow over gate 18 without interruption or leakage. When flow is to be established to the hopper 29 the operative pulls upon rope 32 90 thus withdrawing latches 24 and permitting the front end of gate 18 to drop around pins 17. When flow past hopper 29 is to be re-established the operative pulls upon rope 21 until the gate is restored to the position 95 shown in Fig. 1.

It will be seen that ropes 21 and 32 are entirely protected from the flowing material and it will be understood, of course, that these ropes are extended to any desired 100 point.

I claim as my invention:

1. The combination, with a delivery chute having an opening in its bottom, the upper edges of said opening being shouldered, as 105 at 14, a trough-shaped gate lying outside the chute at its upper end and inside the chute at its lower end and having notches in its

edges receiving the edges of the chute opening, a pivotal support for said gate, an operating arm for the gate, and a latch for holding the gate in closing position.

- 5 2. The combination, with a delivery chute having an opening in its bottom, the upper edges of said opening being shouldered, as at 14, a trough-shaped gate lying outside the chute at its upper end and inside the chute
10 at its lower end, a pivotal support for said gate, an operating arm for the gate, and a

latch for holding the gate in closing position.

In witness whereof, I, have hereunto set my hand at Indianapolis, Indiana, this 28th ¹⁵ day of November, A. D. one thousand nine hundred and thirteen.

WILLIAM H. INSLEY.
